UNITED STATES PATENT OFFICE.

WILLIAM S. FLINDER, OF CHAMBERSBURG, PENNSYLVANIA.

MATCH-BOX.

1,113,425.

Specification of Letters Patent.

Patented Oct. 13, 1914.

Application filed April 22, 1913. Serial No. 762,960.

To all whom it may concern:

Be it known that I, WILLIAM S. FLINDER, a citizen of the United States, residing at Chambersburg, in the county of Franklin 5 and State of Pennsylvania, have invented a new and useful Match-Box, of which the following is a specification.

The present invention appertains to match boxes, and particularly to a device of that 10 character adapted to contain a quantity of matches and to be manually operated to deliver the matches one at a time, to the exterior.

It is the object of the present invention to 15 provide a device of the character indicated of simple construction and operation, which shall embody but a single moving part, or which shall be devoid of springs or other complex parts.

20 Another object of the present invention is to provide means for raising a match from within the match compartment in connection with means for swinging the match to a vertical position and holding it in such a 25 position until removed, the latter means also serving to hold the former means in raised position so that when the match is removed, the former means will gravitate to initial or normal position for a new operation.

30 With the foregoing general objects outlined and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what 35 is claimed without departing from the spirit 40 of the invention.

The invention has been illustrated in its preferred embodiment in the accompanying drawing, wherein:—

45 Figure 1 is a perspective view of the device showing the slide raised with a match held in position to be removed. Fig. 2 is a vertical central section of the device showing the slide in its lowermost or normal position. Fig. 3 is a sectional view taken 50 through the sides of the case and showing the slide raised, parts being broken away.

In carrying out the invention, reference being had in detail to the drawing, there is 55 provided a case or box embodying a back 1, sides 2, a front 3, and a bottom 4, the back

1 extending beyond the ends of the sides and front, and the bottom 4 terminating short of the back so as to provide a lower opening. A cove or top 5 is pivoted between the sides 2 adjoining its rear end, the forward or free end being adapted to normally rest or seat on the front 3 to close the case and the rear end being spaced from the back 1 to provide an opening for the passage for the 60 slide hereinafter referred to. The lower end of the back 1 is extended, as at 6, and has a stop 7 secured thereto.

An upright partition 8 is secured between the sides 2 directly adjoining the back 1 and with its upper edge disposed slightly or at a suitable distance below the upper end of the sides or cover. A chute 9 is also secured between the sides 2 and is declined from the front 3 to the partition 8, the lower or delivery end of the chute being spaced slightly from the partition 8, and the chute forming the bottom of the match compartment. A partition 10 is secured between the sides 2 above the chute 9, the same extending from the cover 5 to a point short of the lower or delivery end of the chute. The partition 10 forms the back wall of the match compartment and constrains the matches to be properly discharged at the lower end of the 75 chute. The partition 8 terminates directly below the end of the delivery chute 9 and is provided with the depending side extensions or legs 11 secured to the sides of the case. The upper edge of the partition 8 is beveled 80 rearwardly, as denoted by the numeral 12, and serves as a ledge for receiving a match raised from the chute 9 as will hereinafter appear.

A slide or plate 13 fits snugly between 95 the back 1 and partition 8 and has its edges slidably engaging the sides of the case, while a supplemental or secondary slide or plate 14 fits snugly between the partition 8 and the lower or delivery end of the chute 9, the slide 13 extending to the lower end of the back 1, while the supplemental slide 14 terminates above the bottom 4 and is securely attached at its lower end to an intermediate point of the slide 13 by means of a yoke 15. The yoke 15 works between extensions or guides 11 and is adapted to contact with the lower edge of the partition 8 when the slide 13 is raised, so as to limit the upward movement of the slide. The slide 13 is adapted 100 to gravitate to initial or normal position, the lower end thereof seating on the stop 7

to properly limit the downward movement of the slide. It is also preferable to secure a strip 16 between the sides adjoining the supplemental or auxiliary slide 14, although this is not necessary, and a block or knob 17 is secured to the lower end of the slide 13 and serves as a finger piece for facilitating the elevation of the slide 13 by hand. When the slide 13 is in its lowermost position, the block 17 is adapted to overlap the stop 7, the lower ends of the back 1 and slide 13 coinciding, which is desirable. When the slide 13 is in its lowermost position, the upper end of the slide 14 will stand adjoining the delivery end of the chute 9, the upper end of the slide 14 being beveled rearwardly, as at 18, to correspond with the inclination of the chute 9. When the slide 13 is in its lowermost position, the upper end thereof will stand adjoining the upper edge 12 of the partition 8, the upper end of the slide 13 being grooved, as at 19, to receive a match delivered from the beveled or inclined edge 12, as will hereinafter appear. When the slide 13 is raised, the yoke 15 is adapted to strike the partition 8 when the upper end 18 of the supplemental slide 14 reaches and coöperates with the upper edge 12 of the partition 8. One upper corner of the slide or plate 13 is cut away or provided with a notch, as designated by the numeral 20, the upright wall of the notch or cut away portion being grooved, as at 21, corresponding with the groove 19. The horizontal wall or side of the notch or cut away portion provides a shoulder or seat 22. An inclined leaf spring 23 is secured at one end to that side 2 of the case adjacent the notch 20 and is disposed adjoining the upper end or top and the back of the case, the free end of the spring being provided with a notch 24 adapted to complement the grooved wall 21. When the slide 13 is raised, the grooved end 19 will project slightly above the cover or top 5, and the spring 23 will be received by the notch or cut away portion 20, the free end of the spring coöperating with the upright wall 21 of the notch. The foregoing parts, with the exception of the spring, are preferably constructed of wood, although other material may be employed with equal propriety, and it is possible to construct the case in various sizes and shapes, or to make other alterations without departing from the spirit of the invention.

In use, the back 1 may be secured to a wall or other upright so as to support the match box or case at a convenient point and out of reach of children, rodents or the like, thus rendering the present device perfectly safe against the premature ignition of the matches.

The present device may be employed for

domestic or business purposes, the matches being readily inserted into the case by swinging the cover 5 open as indicated in dotted lines in Fig. 2. Ordinarily, the slide 13 will gravitate so as to seat on the stop 7 and the matches will roll toward the lower or delivery end of the chute 9. When the slide 13 is raised by hand, this being facilitated by the means of the finger piece 17, the match which has rolled or been delivered from the chute 9 onto the upper end 18 of the supplemental slide 14, will be carried upwardly, and when the slide 13 has reached its uppermost position, so that the yoke 15 strikes the partition 8, the match will roll or be delivered onto the upper edge 12 of the partition 8 to rest against the slide 13 while the slide is in its raised position. Then, when the slide has gravitated, the match will roll or be delivered from the upper edge or ledge 12 of the partition 8 into the groove 19 in the upper end of the slide 13 so that when the slide is raised, one end of the match will be carried toward the spring 23. Thus, as the slide 13 is raised, that end of the match which projects over the notch will first engage the basal or lower portion of the leaf spring 23, so as to slightly raise or swing the other end of the match from the groove 19, until the first mentioned end of the match rests flatly against the bottom of the leaf spring, and when the slide is completely raised, the match will be swung between the free end of the leaf spring and the adjoining corner of the slide, to a vertical or upright position, as seen in Fig. 3. It is to be noted that the entire leaf spring is adapted to yield upwardly to tightly receive the match between the free end of the spring and the upright wall of the notch 20, the upper end of the slide 13 passing slightly beyond the free end of the spring, so that the match will be tightly clamped against the upright wall of the notch. When the match is thus held or clamped within the upright grooved wall of the notch, should downward pressure be applied to the slide, it will be observed that there will be a tendency to swing the leaf spring to a horizontal position, and consequently, the leaf spring will tightly bind the slide against depression. The spring thus serves as a brace between the uprighted match and grooved wall 21 and the corresponding side of the case, to lock the slide against downward movement until the match is withdrawn. The spring, however, is adapted to yield upwardly to permit the match to be readily removed or withdrawn, and after the match has been withdrawn, the spring will be released from the slide, and the slide will thus be free to gravitate to initial or normal position. It is to be observed that after the first operation, each upward movement of the slide will cause one match to be raised 130

from the match compartment onto the ledge 12 and will raise the preceding match from the ledge 12 upward to the vertical position as seen in Fig. 3. Thus, by raising the slide 13, the match may be elevated and held in a vertical position until removed, and when it is removed, the slide will gravitate to its former position for a new operation.

From the foregoing, taken in connection with the drawing, the advantages and features of the present invention will be apparent to those versed in the art, it being noted that the matches may be delivered one at a time, the respective matches being simultaneously raised to initial and final position at each operation of the slide.

Having thus described the invention, what is claimed as new is:—

In a device of the character described, a case including sides, a vertically movable slide having its edges engaging the said sides, the upper end of the slide having a match groove and one upper corner of the slide being notched, the upright wall of the notch having a groove to receive one end portion of a match, and a leaf spring secured

to that side of the case adjacent the said notch, the leaf spring being inclined upwardly from the said side of the case and the free end of the spring having a notch co-operating with the grooved wall of the aforesaid notch, whereby that end of a match carried by the upper end of the slide which projects over the notch will first contact with the basal portion of the spring when the slide is raised to start the upward swinging movement of the other end of the match, and whereby the spring will clamp the first mentioned end of the match within the grooved wall of the notch and will serve as a brace between the match and grooved wall of the notch and the said side of the case to lock the slide against downward movement until the match is withdrawn.

In testimony that I claim the foregoing as my own, I have hereto affixed my signature in the presence of two witnesses.

WILLIAM S. FLINDER.
